UNITED STATES PATENT OFFICE.

JULIUS GOLDZIER, OF CHICAGO, ILLINOIS.

DESIGN FOR A BADGE, PIN, OR BUTTON.

49,181.

Specification for Design.

Patented June 13, 1916.

Application filed March 18, 1916. Serial No. 85,226. Term of patent 3½ years.

To all whom it may concern:

Be it known that I, JULIUS GOLDZIER, a citizen of the United States, residing at Chicago, in the county of Cook, State of Illinois, have invented a new, original, and ornamental Design for a Badge, Pin, or Button, of which the following is a specification, reference being had to the accompanying drawing, forming part thereof.

Figure 1 is a plan view of the article.

Fig. 2 a side elevation of the same.

I claim:

The ornamental design for a badge, pin or button, as shown.

JULIUS GOLDZIER.
